Inventor,

UNITED STATES PATENT OFFICE.

CLINTON W. WELLS, OF LUCAS, IOWA.

WASH-BOARD.

SPECIFICATION forming part of Letters Patent No. 336,186, dated February 16, 1886.

Application filed December 17, 1883. Serial No. 114,819. (Model.)

To all whom it may concern.

Be it known that I, CLINTON W. WELLS, of Lucas, in the county of Lucas and State of Iowa, have invented certain Improvements in 5 Wash-Boards, of which the following is a full, clear, and exact description.

My invention relates to that class of wash-boards which avoids the necessity of the contact of the hands of the operator with the 10 rubbing-surface.

The invention consists in the features of construction and combinations of parts herein-after fully described, and pointed out in the claim.

15 In the drawings, Figure 1 is a plan view of a wash-board constructed in accordance with my invention. Fig. 2 is a central longitudinal section of the same. Fig. 3 is a partial cross-section on the line $x-x$ of Fig. 1.

20 A represents the frame of the board, consisting of parallel sides a a , connected by rounds a' a' and a cross-plate, B. The sides a a of the frame are each provided with an inwardly-projecting cleat or flange, C, to form 25 ways or guides c c for the rubber.

D represents parallel rollers, secured in bearings of the frame A, and constituting the rubbing-surface of the board.

E is the rubber, consisting of a plate or 30 board, e, to which are secured parallel rubbing-ribs e' .

H H are handle-arms secured to the rubber and connected by a bar, I.

The rubber E is adapted to be reciprocated in the guideways c c of the frame by means of 35 a yielding cross-bar, F, supported centrally above the rubber by cross-bars E' E', each provided with a vertically-elongated slot, f, to receive the ends of the bar F. The ends of said bar are recessed to project through the 40 slots f f , and are rounded to form journals f' f' , to receive anti-friction rollers g g , which travel just under the flanges or cleats C C.

G G represent springs interposed between the bar F and rubber E, to permit a ready 45 yielding of the rubber.

J J represent inclined slotted arms, secured near one end of the frame A and provided with thumb-screws K, to facilitate the attachment of the board to a tub or other device. 50

I claim—

In a wash-board, the combination, with a base or frame provided with rollers as a rubbing-surface, and with side pieces provided with flanges C, forming guideways, substantially as described, of a rubber provided with a yielding cross-bar, whose ends are provided with anti-friction rollers to travel in the guideways of the frame, substantially as described. 55

CLINTON W. ^{his} $\times$ WELLS.
